UNITED STATES PATENT OFFICE.

JOHN B. FLINT, OF CHELSEA, AND ARTHUR J. HOWARD, OF MALDEN, MASSACHUSETTS; SAID FLINT ASSIGNOR TO ORLANDO E. LEWIS, OF WINTHROP, MASSACHUSETTS.

NAILING-MACHINE.

SPECIFICATION forming part of Letters Patent No. 562,597, dated June 23, 1896.

Application filed January 16, 1896. Serial No. 575,717. (No model.)

To all whom it may concern:

Be it known that we, JOHN B. FLINT, of Chelsea, in the county of Suffolk, and ARTHUR J. HOWARD, of Malden, in the county of Middlesex, State of Massachusetts, have invented an Improvement in Nailing-Machines, of which the following description, in connection with the accompanying drawings, is a specification, like letters on the drawings representing like parts.

This invention has for its object to improve and simplify the construction of nailing-machines.

The machine here to be described makes its own nails from a flat strip of metal, cutters, to be described, cutting away a portion of one edge of the metal strip at intervals to form the tapering side of the nail and the under side of the head, the nail produced resembling a brad with a head projecting from one side of the body.

Figure 1 represents a left-hand side elevation of a sufficient portion of our improved machine to enable the same to be understood. Fig. 2 is a front elevation thereof. Fig. 3 is an enlarged section in the line *x*, Fig. 2; Fig. 4, an enlarged view showing the inner or active end of the stationary nail-cutter and its carrier. Fig. 5 shows the cam detached; Fig. 6, the nail-cutter and movable carrier; Fig. 7, a detail of the pawl to operate the strip-feeding wheel; Fig. 8, a detail of the forked block. Fig. 9 shows the devices for adjusting the length of the nail, and Fig. 10 shows a nail such as will be produced in the machine.

The column A has a suitable foot, (not shown,) to rest on the floor, and it supports at its top the head A', which is of suitable shape to sustain the working parts.

The main shaft A² has loose on it a driving-pulley A³, having preferably a conical interior, which is adapted to fit against the conical face of a pulley A⁴, fast on said shaft, the loose pulley being pressed in driving contact with the fast pulley by a wedge-fork A⁵, working against the beveled end of a loose collar A⁶, the opposite end of which acts against the hub of the pulley A⁴, the wedge being attached to a rod A⁷, connected in practice with a suitable treadle, the spring A⁸ acting normally to separate the said pulleys.

The pulley A³ has attached to, or forming part of it, a large wheel A⁹, herein shown as having a V-shaped groove in its periphery, which groove receives a wheel A¹⁰, having a ⁵⁵ A-shaped periphery, said wheel being fast on a shaft A¹¹, carrying a grinding-wheel A¹².

The front end of the shaft A² has attached to it a driver-lifting cam B, which acts on a lug of a collar B', fixed on the driver-bar B², ⁶⁰ having a driver B³, said cam lifting the bar, and a suitable spring B⁴, acting on a lever B⁵ to depress the said bar. The shaft A² also has fast on it a disk B⁶, (shown separately in Fig. 5,) said disk having at its front side a cam-⁶⁵ groove B⁷, (shown by full lines,) and at its rear side a cam-groove B⁸. (Shown by dotted lines.)

The cam-groove B⁷ receives a roller or other stud of a lever B⁹, pivoted at B¹⁰, and having ⁷⁰ at its lower end a segmental toothed rack which engages the teeth of a pinion B¹², fast on a short shaft C¹³, having at its outer end a pawl-carrying arm C, having at its inner side a pawl C', pivoted at C² and acted upon by a ⁷⁵ suitable spring C³, (see Fig. 7,) said pawl being normally acted upon by said spring to cause it to engage the teeth of a ratchet-wheel C⁴. This pawl has a constant throw, and the pawl would consequently always have ⁸⁰ a definite stroke and would move the strip-feeding wheel C⁵ a definite distance, causing its acting against one edge of the strip *a* to feed always for a like distance, and the nails would all be of a certain length; but to enable the machine to make nails of any desired ⁸⁵ length this pawl has combined with it a shield C⁶, attached, as shown in Fig. 1, by screws to the end of a length-adjusting lever C⁸, having its fulcrum on the shaft C¹³ alongside the ⁹⁰ ratchet-wheel C⁴, and by moving this lever the shield may be interposed between the ratchet-wheel and the pawl, so that the effective stroke of the pawl in moving the ratchet-wheel may be altered, as desired, to cause the ⁹⁵ strip to be fed for a greater or less distance, according to the length of nail desired. This lever is moved by hand and has a spring-actuated locking-pin C¹⁰, which co-operates with a toothed segment C¹¹, fast on the machine-head, the locking-pin holding the lever in adjusted position.

¹⁰⁰

The disk B⁶ has ratchet-teeth at its periphery, which are engaged by a pawl b to prevent the shaft a² turning backward.

The strip a is taken from a roll a', suitably 5 mounted on the machine, and is led through a suitable guide a² and thence between the toothed feed-roll C⁵ and a coöperating roll a³, mounted on a stud carried by a lever a⁴, pivoted at a⁵ and having combined with its end 10 a pressure-adjusting device, shown as a screw a⁶, the end of which abuts against the framework so that the effective pressure or force with which the said strip is grasped may be varied, and by using a narrow strip and feed- 15 ing it by grasping its edges we find it possible to cause the teeth of the feed-wheel C⁵ to so embed themselves into the edge of the strip as to indent the same, leaving a series of scores or teeth, as a⁷, (see Fig. 10,) at the straight 20 edge of the tapering-bodied nail, said scores or teeth adding very materially to the holding power of the nail. After passing below the feed-wheels the strip enters a guideway a⁸, (shown best in Fig. 4,) the said guideway being 25 made from a steel block suitably grooved for the passage of the wire, the lower hardened end of said guide terminating substantially flush with the shoulder a⁹ of a projecting portion a¹⁰ of the framework.

30 The machine has pivoted upon it at b a lever b', provided at the inner side near its outer end (see Fig. 3) with a steel block b², having a strip-receiving groove b³ and a lip b⁴, provided with a notch b⁵ in line with said groove 35 b³, the said lip, in practice, traveling close under the shoulder a⁹ and acting with the hardened end of the guide a⁸ to cut the strip transversely into nail lengths.

The lever b' has upon it a loose block b⁶, 40 kept in place by a collar b⁷, and the said loose block is embraced by a forked block b⁸, having a shank b⁹, which is entered loosely into a hole at the lower end of a lever b¹⁰, pivoted at b¹¹ and having a roller or other stud b¹² at 45 its upper end which enters the cam-groove b¹³, before described. The loose fork enables the two levers b¹⁰ and b', one in a vertical and the other in a horizontal plane, to work freely.

The head of the machine has connected to 50 it by suitable screws c a plate c', having a tubular nose c², down through which the nail is driven by the driver into the work, the said nose resting on the work presented by the hand of the operator, usually the sole of a 55 shoe. Above the plate c' the head has a passage in which is placed side by side a stationary cutter c³ and a back or holding plate c⁴, said plate being, however, adjustable longitudinally. The cutter c³ is held by a suitable 60 screw, as c⁵, and the screw c⁵ enters by its inner end the plate c⁴, the hole in which the screw c⁵ stands being somewhat elongated to enable the said screw to be moved laterally and with it the plate c⁴, for the inner end of 65 said plate acts as a guide for one edge of the strip a when the latter is thrust through into the slots b⁵ and b³, the lever b' at such time

being so moved as to place the said slots in line vertically with the guiding-slot at the lower end of the guide a⁸, the slots b⁵ b³ being 70 at such time behind the face of the cutter c³, viewing the machine from the front side.

The grooves b⁵ and b³ having received the end of the strip, the lever b' is moved, causing the strip to be cut off between the upper 75 side of the lip b⁴ and the lower end of guideway a⁸ and at the same time the portion of the strip in said grooves b⁵ and b³, especially the portion below the lip b⁴, is borne against and carried past the stationary cutter, causing 80 the latter to clip or cut out from the edge of the strip a tapering piece, leaving a head of the full width of the strip and of a depth equal to the depth of the lip b⁴, and the lever b' continues its movement in the direction in 85 which it started until the grooves b⁵ and b³ arrive opposite the driving-groove e, made in a steel block e', held in place by a suitable screw e², there being a space f above said block for the passage of the lip and the head 90 of the nail over the end of the block in coming into line with the groove e.

The block b² is held in place by a suitable screw e⁴, and it constitutes the movable cutter member which coöperates with the stationary 95 cutter member c³, and it also by its lip not only cuts off the strip, but also determines the shape of the head of the nail.

The bearing D, in which the shaft A¹⁰ turns, has a shank D², which enters a hole in an ear 100 D³ of the column, the shank being held in adjusted position by a set-screw D⁴. The bearing has a hole to receive a rod d, held in place by a set-screw D' and inclined with relation to the shaft A¹⁰. This rod has mounted on it 105 the hub of a blade-holder d', having its upper side inclined from a horizontal plane and adapted to support the cutter-blade c³.

The blade-holder has a lip d², provided with a screw d' to keep the blade seated, and screws 110 d⁵ d⁶ act on the outer end of the blade to hold and adjust it.

The grinding-wheel is used to grind and keep the cutting edges of the blade sharp.

It will be noticed, viewing Fig. 4, that the 115 cutter c³ is set at an inclination to a vertical plane, so that it acts with a shearing cut on the strip, it meeting the strip first close to the under side of the lip b⁵, and thereafter acting gradually to shear the metal to the point. 120

Having described our invention, what we claim as new, and desire to secure by Letters Patent, is—

1. In a nailing-machine, the lever b' having a cutting-die provided with a lip, the said die 125 and lip having coinciding grooves, and a block having a driver passage with a space above it for the head of a nail, combined with a guide for the strip being fed into the slots of the lip and cutting-die, and with a stationary cutter 130 adapted to cut out a portion of one edge of the strip and leave a head and a tapering edge below it, substantially as described.

2. In a nailing-machine, the shaft A², its

cam B⁸, a lever having a yoke provided with a shank held loosely in said lever, combined with the cutter-lever b' having an attached cutting-block provided with a lip, and a loose block b⁶ fitted on said lever, substantially as described.

In testimony whereof we have signed our

names to this specification in the presence of two subscribing witnesses.

JOHN B. FLINT.

ARTHUR J. HOWARD.
